HOLDER AND DISPENSER FOR
COLLAPSIBLE TUBES

Frederick A. Major, St. Louis, Mo.

Application October 18, 1950, Serial No. 190,763

4 Claims. (Cl. 222—100)

1

This invention relates generally to devices for holding and expelling from collapsible tubes the contents thereof, and more specifically to such a device which is simple in construction and efficient in operation, the predominant object of the invention being to provide a device of the type referred to above in the use of which a predetermined measured amount of the contents of a collapsible tube is expelled from the tube in a sanitary manner on each operation of the device.

Fig. 1 is an end elevation of the improved device of the invention.

Fig. 2 is a side elevation of the device illustrated by Fig. 1 with a part thereof shown in a changed position by broken lines.

Fig. 3 is a section taken on line 3—3 of Fig. 1.

Fig. 4 is a fragmentary, enlarged view of part of the mechanism shown in Fig. 3.

Fig. 5 is an enlarged section taken on line 5—5 of Fig. 1.

Fig. 6 is a section taken on line 6—6 of Fig. 2.

In the drawing, wherein is shown for purposes of illustration, merely one embodiment of the invention, A designates the improved holding and dispensing device generally. The device A includes a base plate 1 from which is extended upwardly a pair of spaced bearing elements 2, said bearing elements being provided with bearing openings in which is supported for rotation a shaft 3. The shaft 3 is provided at an end thereof with a finger grip 4 which serves to facilitate rotation of said shaft, and also said shaft is provided with a slot 5 that extends longitudinally thereof, said slot being open at an end of the shaft and at opposed side portions thereof.

The device A is provided with tube holding means 6 which comprises an annular portion 7 having a pair of opposed curved legs 8 and 9 extended downwardly therefrom. The leg 8 is hinged at its lower end between a pair of spaced ears 10 which extend upwardly from the base plate 1 by a hinge pin 11 and because of this arrangement the tube holding means 6 may be moved to the position in which it is shown by broken lines in Fig. 2 when a tube is to be introduced in place in the device or removed therefrom.

The shaft 3 has rigidly mounted thereon a ratchet wheel 12, and loosely mounted on said shaft for oscillatory movement with respect thereto in an operating arm 13. The operating arm 13 supports a pawl 14, said pawl being supported for pivotal movement by a pivot element 15 and having associated therewith a torsional coil spring 16 that tends to urge the nose por-

2

tion of said pawl into engagement with the teeth of the ratchet wheel 12. By referring to Fig. 4 of the drawing it will be noted that one end portion of the torsional coil spring contacts with a lug 17 which is formed on the operating arm 13 while at the other end of said torsional coil spring an end portion of the spring is projected into an aperture formed in the pawl 14. The operating arm 13 has associated therewith a torsional coil spring 18 whose coiled portion embraces the shaft 3 inwardly of the finger grip 4 thereof, one end portion of said torsional coil spring 18 being engaged by an element 19 associated with the base plate 1, and an end portion 15 of the torsional coil spring 18 at the opposite end thereof being projected into an aperture formed in a portion of the operating arm 13. The operating arm is provided with a screwthreaded abutment element 20 which serves to limit downward movement of the operating arm 13 by contacting with the base plate 1, said abutment element being supported in a screwthreaded opening formed through the lug 17 and said abutment element being adjustable so as to regulate 20 the extent of the operating stroke of the operating arm 13.

In the use of the improved device of the present invention, the shaft 3 and the various parts of the unit of which said shaft forms a part are removed from the device by pulling the shaft longitudinally of its major axis so as to disengage said shaft from the bearing elements 2. The tube holding means 6 is then moved to the position in which it is shown by broken lines in Fig. 2 and a tube T is extended through the annular portion 7 of said tube holding means. The shaft 3 is replaced in position with respect to the bearing elements 2 of the device, the flattened lower end portion of the tube being caused to be disposed in the slot 5 of said shaft, and the tube holding means 6 is moved to its normal vertical position. The device A is now ready for use, it being necessarily merely to remove the cap of the tube and depress the operating handle 13 to receive from the tube a predetermined measured amount of the contents of the tube, part of the contents of the tube being expelled therefrom because a lower portion of the tube is wound on the shaft 3 upon rotation of said shaft (see Fig. 5). If, however, a user should prefer not to have a predetermined amount of the contents of the tube expelled therefrom on operation of the device A. The finger grip 4 of the shaft may be grasped and the shaft rotated to the desired degree, the ratchet wheel 12 during such opera-

tion of the device rotating idly relative to the pawl 14, as is indicated by the arrow in Fig. 4.

I claim:

1. A device for holding a collapsible tube and expelling therefrom the contents thereof in measured amounts, said device comprising a base member, a tube holding means having a portion which embraces the collapsible tube and a pair of leg portions extended from said tube-embracing portion, pivot means for pivoting one of said leg portions of said tube holding means to said base member so as to support said tube holding means for pivotal movement with respect to said base member, the other of said legs contacting with said base member for maintaining said tube holding means in its normal position with respect thereto, a shaft supported for rotation by said base member, and having a slot formed longitudinally thereof which receives a portion of the tube so that said tube may be wound on said shaft on rotation of said shaft, and means for subjecting said shaft to a predetermined degree of rotation on each operation of said means so as to expel a predetermined amount of the contents of the tube on each such operation.

2. A device for holding a collapsible tube and expelling therefrom the contents thereof in measured amounts, said device comprising a base member, a tube holding means having a portion which embraces the collapsible tube and a pair of curved leg portions extended from said tube-embracing portion, pivot means for pivoting one of said leg portions of said tube holding means to said base member so as to support said tube holding means for pivotal movement with respect to said base member, the other of said legs contacting with said base member for maintaining said tube holding means in its normal position with respect thereto, a shaft supported for rotation by said base member, and having a slot formed longitudinally thereof which receives a portion of the tube so that said tube may be wound on said shaft on rotation of said shaft, and means for subjecting said shaft to a predetermined degree of rotation on each operation of said means so as to expel a predetermined amount of the contents of the tube on each such operation.

3. A device for holding a collapsible tube and expelling therefrom the contents thereof in measured amounts, said device comprising a base

member, a tube holding means having a portion which embraces the collapsible tube and a pair of leg portions extended from said tube-embracing portion, pivot means for pivoting one of said legs portions of said tube holding means to said base member so as to support said tube holding means for pivotal movement with respect to said base member, the other of said legs contacting with said base member for maintaining said tube holding means in its normal position with respect thereto, a shaft supported for rotation by said base member, and having a slot formed longitudinally thereof which is open at an end of said shaft and receives a portion of the tube so that said tube may be wound on said shaft on rotation of said shaft, and means for subjecting said shaft to a predetermined degree of rotation on each operation of said means so as to expel a predetermined amount of the contents of the tube on each such operation.

4. A device for holding a collapsible tube and expelling therefrom the contents thereof in measured amounts, said device comprising a base member, a tube holding means having a portion which embraces the collapsible tube and a pair of leg portions extending from said tube-embracing portion, pivot means for pivoting one of said leg portions of said tube holding means to said base member so as to support said tube holding means for pivotal movement with respect to said base member, the other of said legs contacting with said base member for maintaining said tube holding means in its normal position with respect thereto, a shaft supported for rotation by said base member, and having a slot formed longitudinally thereof which receives a portion of the tube so that said tube may be wound on said shaft on rotation of said shaft, a finger grip at an end of said shaft and means for subjecting said shaft to a predetermined degree of rotation on each operation of said means so as to expel a predetermined amount of the contents of the tube on each such operation.
